UNITED STATES PATENT OFFICE.

LOUIS STEINBERGER, OF NEW YORK, N. Y.

LOCKING-INSULATOR.

SPECIFICATION forming part of Letters Patent No. 783,229, dated February 21, 1905.

Application filed March 19, 1903. Serial No. 148,556.

To all whom it may concern:

Be it known that I, LOUIS STEINBERGER, a citizen of the United States, and a resident of the city of New York, borough of Brooklyn, 5 in the county of Kings and State of New York, have invented a new and Improved Locking-Insulator, of which the following is a full, clear, and exact description.

My invention relates more particularly to 10 an improved insulator for carrying wires for electric light and power and for telegraph and telephone services and in all other relations where wires are required to be insulated from their supports.

15 My invention saves time and money now wasted on tie-wires. By its use even an unskilled workman is able to fasten and lock the wire to the insulator. It also tends to save battery-power now wasted incidental to leakage from tie-wires and is ready for mounting 20 without the use of pins and boring-tools.

Reference is to be had to the accompanying drawings, forming a part of this specification, in which similar characters of reference indicate 25 corresponding parts in all the figures.

Figure 1 shows a central section through one form of my locking-insulator. Fig. 2 is a fragmentary section otherwise somewhat similar to Fig. 1, but showing a boss 16 partly 30 broken away. Fig. 3 is a fragmentary section otherwise somewhat similar to Fig. 1, but showing the metallic face 17^a as not engaging the wire. Fig. 4 is a central section through my preferred form, and Fig. 5 is a horizontal 35 section upon the line 5-5 of Fig. 4 looking toward the bottom of the drawing.

In Figs. 1, 2, and 3 the body 1 of the insulator is provided internally with a thread 2 and with a petticoat 3. In Fig. 4 the body 4 40 is rigidly mounted upon a screw-bolt 5, which is threaded at 7 for the purpose of mounting the insulator. In this form the screw-bolt is surrounded by a concavity 8. In both forms the groove 9 is provided for the wire. Where 45 either form is used, the upper end of the body portion is provided with a slot 10, which is provided with an enlarged portion 13 and separates the two parts 11 12, as indicated more particularly in Fig. 5. The upper end of the 50 body portion is provided at 14 with threads.

The cap 15 is threaded internally and screwed upon the body portion, as shown in all of the figures.

Mounted centrally within the cap 15 is a boss 16 of substantially frusto-conical form 55 and provided at its lower end with a concave surface 16^a. The wire 18 is disposed within the slot 10 and directly crosses the enlarged portion 13 thereof, and then the cap 15 is screwed down firmly into position, so that the 60 boss 16 will normally engage the wire. An annular facing 17, of metal, is provided with an annular portion 17^b, whereby the same is rigidly connected with the outer portion of the cap 15. Should the facing 17 be broken or 65 from any other cause fail to make a perfect fit, as indicated at 17^a, the boss 16 grips the wire and holds the same firmly in position. On the other hand, if the boss 16^a chances to be broken or if from any other cause this boss 70 fails to bind upon the wire the metallic facing 17 will nevertheless hold the wire in position, as indicated in Fig. 2.

The annular facing 17 may be connected with the caps 15 15^a in a variety of ways, depending to some extent upon the nature of the material of which the insulating portion 15 is made. I preferably make this portion of the insulating substance commercially known as "electrose." This material is plastic and 75 may be molded into any desired form. When forced under pressure into a mold and into contact with the facing 17, it adheres perfectly and forms a rigid connection. It is sufficiently elastic to sustain considerable stress 85 without breaking or chipping off and has none of the objectionable brittle qualities peculiar to glass. The electrose when in plastic form is pressed directly against the metallic facing, so as to spread upon both sides of the annular 90 web portion 17^b. The insulator provides great strength where the same is most needed. By its use a metallic surface is placed in direct contact with the wire, so as to lock the same in an efficient and reliable manner. When 95 thus made, the insulator will last indefinitely. The device embodying the construction just mentioned is for the purpose of affording a plurality of points which bear independently upon the surface of the wire, so that if the 100

pressure at one point should fail to hold the wire the pressure at other points will be effective for the purpose. In cases where the screw-bolt 5 is used, as indicated in Fig. 4, as 5 the head 6 is firmly embedded in the substance of the insulation 4, the screw-bolt and the insulating body portion virtually constitute a single part of great strength and which may be applied by merely screwing the threaded portion 7 into a wooden support.

In Fig. 4 the cap 15^a is provided integrally with an umbrella-shaped shield or web 15^b. The purpose of this shield is to ward off rain, sleet, &c., from the annular member 17 and 15 from the wire 18 at the points where it is engaged, thereby to prevent leakage due to moisture.

It will be seen that the annular metallic facing not only binds the wire in position, but 20 serves also to strengthen the cap to which it is connected.

I do not limit myself to any particular shape for the slot 10 or the enlargement 13. Neither do I limit myself to the exact construction of 25 any of the other several parts shown.

Having thus described my invention, I claim as new and desire to secure by Letters Patent—

1. A locking-insulator, comprising a body portion provided with a surface for engaging 30 a wire, a cap of insulating material detachably connected with said body portion, and an annular facing of metal rigidly connected with said cap of insulating material for engaging said wire.

35 2. As an article of manufacture, a cap provided with a weather-shield and with a metallic face disposed adjacent to said weather-shield and adapted to be kept dry thereby.

3. As an article of manufacture, a cap provided with an annular portion, and an annular metallic member connected rigidly with 40 said portion and provided with a bearing-surface, said cap being further provided with a rain-shield integral therewith and adapted to 45 project over said metallic member.

4. As an article of manufacture, a revolvable cap made of insulating material and provided with a metallic member molded upon said cap.

50 5. As an article of manufacture, a cap of in-

sulating material having an annular portion, and a metallic member of general annular form connected rigidly with said annular portion, said cap being further provided with a screw-thread.

55 6. As an article of manufacture, a cap made of insulating material provided with annular groove, and a metallic member provided with a portion projecting into said groove and immoveable relatively thereto for the purpose of 60 securing said metallic member and said cap firmly together.

7. As an article of manufacture, a cap made of insulating material and provided with an annular portion having an annular groove concentric therewith and disposed centrally thereof, and a metallic ring provided with an annular portion engaging said groove and also provided with a bearing-surface.

70 8. As an article of manufacture, a cap made of insulating material and provided with an annular portion, and an annular member of metal anchored to said annular portion, being thus permanently secured thereto.

9. As an article of manufacture, a cap provided with an annular edge of insulating material, and a metallic member mounted upon said edge of insulating material for the purpose of strengthening the same.

80 10. As an article of manufacture, a member of insulating material and an annular metallic member connected rigidly therewith and forming a bearing edge therefor, said member of insulating material being further provided with means whereby it may be mounted.

85 11. As an article of manufacture, a member of insulating material provided with an annular portion, and an annular metallic member connected rigidly with said annular portion and forming a bearing edge therefor, said 90 member of insulating material being further provided with means whereby it may be mounted.

In testimony whereof I have signed my name to this specification in the presence of two sub- 95 scribing witnesses.

LOUIS STEINBERGER.
